UNITED STATES PATENT OFFICE.

FRANCIS T. KERNS, OF BEHLER, WEST VIRGINIA.

OIL-SAVING DEVICE FOR OIL-WELLS.

1,159,230.

Specification of Letters Patent.

Patented Nov. 2, 1915.

Application filed October 29, 1913. Serial No. 797,922.

To all whom it may concern:

Be it known that I, FRANCIS T. KERNS, a citizen of the United States, residing at Behler, in the county of Monongalia and State of West Virginia, have invented certain new and useful Improvements in Oil-Saving Devices for Oil-Well; and I do hereby declare the following to be a full, clear, and exact description of the invention, such as will enable others skilled in the art to which it appertains to make and use the same.

This invention relates to improvements in oil saving devices and has for its primary object to provide a simple, practical and efficient oil saver to be used when tubing is being drawn from a well.

Another object of the invention is to provide an oil saving device including a tubular body formed in two substantially semi-cylindrical sections, means for clamping said sections together around a joint in a line of tubing, and means for conveying oil from within said body.

Another and more important object of the invention is to provide in a device of this nature means for engagement with a pair of tongs whereby the device will be held in position as the tube sections are uncoupled.

With these and other objects in view as will become more apparent as the description proceeds, this invention consists in certain novel features of construction, combination and arrangement of parts as will be hereinafter more fully described and claimed.

For a complete understanding of my invention, reference is to be had to the following description and accompanying drawings, in which—

Figure 1 is a side elevation of my improved oil saving device, showing the same in operative position. Fig. 2 is a side elevation, showing the device open. Fig. 3 is a horizontal section taken on the plane of line 3—3 of Fig. 1. Fig. 4 is a fragmentary vertical section taken on the plane of line 4—4 of Fig. 1. Fig. 5 is a fragmentary sectional view showing how one of the packing strips is secured in position, and Fig. 6 is a horizontal sectional view taken on the plane of line 6—6 of Fig. 1.

Referring in detail to the drawings by numerals, 5 designates as an entirety my

improved oil saving device which has a 55 tubular body open at each end and formed of substantially semi-frusto-conical sections 6 and 7 which are hinged to each other as indicated by the numeral 8. The longitudinal edges of the section 7 are grooved 60 as indicated by the numeral 9 to receive the gaskets or packing strips 10. These strips extend the full length of the section, may be made of any suitable material, such as leather or rubber, and are secured in position by means of any suitable fasteners 11. The longitudinal edges of the section 6 are formed with longitudinal grooves 12 into which the packing strips 10 are received when the sections are clamped together. 70 Each section also carries adjacent its upper and lower edges the transverse gaskets or packing strips 13 which are received within grooves 14 and which extend between the packing strips 10 and grooves 12. 75

To clamp the sections together, I provide an eccentric lever or latch 15 which is connected by the links 16 to a projection 17 formed upon the section 7 adjacent the free longitudinal edge thereof, and which is 80 adapted to lockingly engage a similar projection 18 formed adjacent the free longitudinal edge of the section 6. The projection 18 is formed with the concave face 19 which is engaged by the head 20 of the latch 85 or lever.

Oil may be conveyed from the interior of the body to any suitable receptacle by means of a pipe or tube, not shown, connected in the tapped opening 21 formed in the section 90 7 adjacent the lower end thereof.

The sections 6 and 7 are thickened or notched centrally of their longitudinal edges adjacent their lower ends by forming thereon the offsets 22 and these thickened portions 95 are provided with transverse grooves or channels 23. These channels extend entirely through the sections, open upon the lower edges thereof, have their upper walls disposed in horizontal planes, and their side 100 walls converging downwardly and inwardly. A jaw 24 slides within each of the channels or recesses 23 and has a shank which appears dovetailed in cross section or which conforms to the recesses. The outer ends of 105 the shanks are extended downwardly and then inwardly to form the gripping portions 25 of the jaw. Set screws 26 thread down-

wardly through the upper portions of the offsets 22 and engage the shanks of the jaws to lock said jaws in their adjusted positions.

In operation the device is clamped about 5 a tubing section 27 and a collar or coupling 28, which operation may be conveniently performed by means of the hand projections 29 formed on the sections 6 and 7. The upper packing strips 13 engage the tubing 27, 10 and the lower packing strips engage the coupling 28. These packing strips together with the packing strips 10 form a sealed chamber about the tube and coupling. Before unscrewing the tube 27 from the 15 coupling 28, it is customary to grasp the latter and hold it firmly against rotation by means of a pair of tongs 30. Having gripped the coupling with the tongs 30, the jaws 24 are engaged with the tongs, 20 as shown in Figs. 1 and 4, whereby the oil saver is prevented from turning or otherwise moving from its proper position when the tube 27 is unscrewed. This locking feature is a very important feature of my invention, 25 as it is essential that some means be provided for holding the oil saver against rotational and longitudinal movement.

While I have shown and described the preferred embodiment of my invention, it will 30 be understood that minor changes in construction, combination and arrangement of parts may be made without departing from the scope and spirit of the invention as claimed.

Having thus described my invention, I 35 claim:

1. In a device of the character described, a tubular body having a discharge opening formed therein, and adjustable means carried by said body adapted for engagement 40 with a stationary member whereby the body is held against rotational and longitudinal movement.

2. In a device of the character described, a body comprising a pair of hinged semi-frusto-conical sections, means for locking said sections in their closed positions, the lower edges of the sections being transversely recessed, and jaws slidable within said recesses, the jaws being adapted to engage 45 a stationary element to hold the body against movement.

3. In a device of the character described, a body comprising a pair of hinged semi-frusto-conical sections, means for locking 55 said sections in their closed positions, the lower edges of the sections being transversely recessed, jaws slidable within said recesses, and set screws for locking the jaws in any adjustable position, the jaws being 60 adapted to engage a stationary element to hold the body against movement.

In testimony whereof I affix my signature in presence of two witnesses.

FRANCIS T. KERNS.
